(57) **CLAIM**

I claim the ornamental design for a toggle switch cover, as shown and described.

DESCRIPTION

FIG. 1 is a front perspective view of a toggle switch cover in a wall plate showing my design;

FIG. 2 is a front perspective view of the toggle switch cover removed from the wall plate;

FIG. 3 is a rear perspective view thereof;

FIG. 4 is a front elevational view thereof;

FIG. 5 is a top elevational view thereof, the bottom elevational view being identical;

FIG. 6 is a right elevational view thereof, the left elevational view being identical;

FIG. 7 is a rear elevational view thereof;

FIG. 8 is a top sectional view taken generally about line 8-8 in FIG. 7; and,

FIG. 9 is a right sectional view taken generally about line 9-9 in FIG. 7.

The broken lines shown in the Figures are included for the purpose of illustrating environmental features and form no part of the claimed design.
